LEADING EDGE STRUCTURE FOR AIRFOIL

John M. Ellison, Gardena, Raymond J. Moore, Long Beach, and Russell J. Pease, Gardena, Calif., assignors to Northrop Aircraft, Inc., Hawthorne, Calif., a corporation of California

Application January 19, 1952, Serial No. 267,252

2 Claims. (Cl. 244—123)

Our invention relates to sheet stiffeners and more particularly to metal sheets having a backing of "styrofoam," an extremely light expanded form of polystyrene plastic, bonded thereto.

In airplane structures, a multiplicity of skin stiffeners are utilized in what is well known as stressed skin construction. These stiffeners are usually in the form of ribs or light corrugated sheet attached to the inner side of the airplane skin sheets exposed to the airstream in flight.

It is an object of the present invention to provide a sheet stiffener in contact with and securely bonded to substantially the entire free skin area of the sheet.

In brief the present invention includes a metal sheet having a body of styrofoam bonded thereto with an adhesive having high strength bonding characteristics to both the metal and the styrofoam. A preferred structural form of the invention is a sandwich, with styrofoam between two metal sheets and bonded to both. The styrofoam stabilizes the sheet to which it is attached, the styrofoam core resisting the greater part of the shear stresses.

The single figure shows an airplane leading edge member stiffened in accordance with the present invention. This edge member is essentially a sandwich with one side closed.

In the figure, a metal sheet 1 of aluminum alloy is formed into a conventional leading edge member 2 for an airplane control surface, for example, the member 2 having the customary laterally extending stiffeners 3 attached thereto inwardly and rearwardly of the leading edge 4. An interior filler 5 of "styrofoam" (foamed polystyrene plastic) is cut from a block of the material to fit the interior of member 2. In order that maximum stiffening be obtained, the filler 5 is securely bonded to the interior surfaces of sheet 1 and to the front surfaces of lateral stiffeners 3. A satisfactory strong bond to both metal and foam is obtained by the use of the following adhesive:

100 parts by weight of "Epon L-1372" (100% solids)
76 parts by weight of methanol
8% of diethylenetriamine catalyst based on the resin content of the resultant solution

NOTE.—"Epon" as at present marketed is a polymeric condensation product resulting from the reaction of epichlorohydrin and the phenol 4,4' dihydroxy diphenyl

2

dimethyl methane. The adhesive solution when applied has a viscosity of 32 seconds at 70°+ as measured by a ZHAN viscosimeter.

5 The above adhesive is not per se a claimable part of the present invention; but forms the subject of the pending U. S. application Ser. No. 240,179, filed August 3, 1951, by Pease.

This adhesive is placed between all metal and styrofoam surfaces to be bonded and allowed to air dry at 10 room temperature for about five hours. No stresses should be applied for about 24 hours thereafter. The resultant structure has been found to be stronger and lighter than the usual honeycomb core type of stiffener heretofore used in similar structural members. It is also 15 easier to cut, and to fit into the member.

While in order to comply with the statute, the invention has been described in language more or less specific as to structural features, it is to be understood that the invention is not limited to the specific features shown, 20 but that the means and construction herein disclosed comprise the preferred form of putting the invention into effect, and the invention is therefore claimed in any of its forms or modifications within the legitimate and valid scope of the appended claims.

25 What is claimed is:

1. A stressed skin leading edge structure for aircraft wings and the like; comprising a unitary metal sheet formed to define a spanwise extending hollow leading edge structure of airfoil cross section, a preformed core 30 of low density material separately shaped to fit and completely fill the hollow interior of said leading edge structure and forming the sole support for said skin, a layer of air drying adhesive between the interior surface of said metal sheet and the exterior surface of said core, the 35 rear edges of said metal sheet being supported by spanwise extending stiffeners adapted to define faying edges for attaching said leading edge structure to the center section of an aircraft wing or the like.

2. A stressed skin leading edge structure according to 40 claim 1 wherein said low density material is foamed polystyrene.
